UNITED STATES PATENT OFFICE

114,551

DESIGN FOR A COASTER

John R. Morgan, Oak Park, Ill., assignor to Sears, Roebuck and Co., Chicago, Ill., a corporation of New York

Application October 17, 1938, Serial No. 80,493

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Coaster, of which the following is a specification, reference being had to the accompanying drawing, forming a part thereof.

Fig. 1 is a top plan view of a coaster embodying my new design.

Fig. 2 is an elevational view thereof.

Fig. 3 is an enlarged fragmentary sectional view taken substantially as indicated by the line 3—3 in Fig. 1.

I claim:

The ornamental design for a coaster, substantially as shown.

JOHN R. MORGAN.
